DESIGN FOR A SHUTTER CASING FOR CAMERAS

Harry R. Darling, Rochester, N. Y.

Application February 23, 1939, Serial No. 83,168

Term of patent 14 years

To all whom it may concern:

Be it known that I, Harry R. Darling, citizen of the United States of America, residing in Rochester, in the county of Monroe and State of New York, have invented a new, original, and ornamental Design for a Shutter Casing for Cameras, of which the following is a specification, reference being had to the accompanying drawing, forming a part thereof.

In the drawing:

Fig. 1 is a front plan view of a shutter casing for cameras showing my new design.

Fig. 2 is a side elevation of a shutter casing for cameras shown in Fig. 1.

Fig. 3 is a back plan view of a shutter casing for cameras shown in the preceding figures.

I claim:

The ornamental design for a shutter casing for cameras, as shown.

HARRY R. DARLING.
